LUBRICATING DEVICE FOR SEWING MACHINES

Sydney Zonis, Bridgeport, Conn., assignor to The Singer Manufacturing Company, Elizabeth, N. J., a corporation of New Jersey

Application December 9, 1943, Serial No. 513,567

7 Claims. (Cl. 112—256)

This invention relates to lubricating devices for sewing machines and has for its object to provide improved means for supplying lubricant to the crank-pin of a crank-member; the invention being particularly adapted for use in supplying lubricant to the needle-bar reciprocating crank-member of a sewing machine in which the bracket-arm shaft is rotatably journaled in an anti-friction bearing adjacent said crank-member.

The invention consists in the lubricant-collecting and conducting devices, combinations and arrangements of parts hereinafter described in connection with the accompanying drawing, which illustrate a preferred embodiment of the invention and in which:

Fig. 1 represents an enlarged vertical section of the bracket-arm head portion of a sewing machine, the section being taken in substantially the vertical plane containing the rotation-axis of the arm-shaft. Fig. 2, taken substantially along lines 2—2 of Fig. 1, represents a fragmentary vertical section taken transversely of the arm-shaft of the machine in front of the oil-well segment-plate which is shown as partly broken away. Fig. 3 represents a perspective view of the oil-well segment-plate.

The sewing machine in part illustrated in the drawing has a frame including a hollow bracket-arm 1 terminating in a head 2 provided with a face-plate 3. Adjacent the head 2, the bracket-arm 1 is internally provided with a transverse wall 4 having an opening 5 to receive an anti-friction shaft-bearing in the form of a ball-bearing 6. The ball-bearing 6 extends in part beyond the wall 4 at the head 2 side of said wall.

Rotatably journaled in the ball-bearing 6 is a horizontally disposed needle-reciprocating arm-shaft 7 which extends lengthwise through the opening 5 into the bracket-arm head 2. Secured upon the end of the arm-shaft 7 within the head 2, by means of a screw 8, is a counter-balanced crank-member 9; said crank-member having at one side thereof a short cylindrical hub-extension 10 in contact with the inner race-ring of the ball-bearing 6. The crank-member 9 is provided with an opening 11 in which a horizontally disposed crank-pin 12 is secured by a set-screw 13; said crank-pin 12 having the end thereof proximate to the ball-bearing 6 disposed substantially flush with the corresponding face of the crank-member 9. At its outer end, the crank-pin 12 has a flange or head 14 which carries one of two connected needle-thread take-up disks 15.

Between its ends, the crank-pin 12 is provided with a circumferential flange 16 spaced from the

crank-member 9 and from a washer 17 which embraces the crank-pin 12 and is disposed in a suitably recessed portion of the crank-member 9.

Journalized by means of a needle-roller bearing 18 upon the crank-pin 12 and confined by the flange 16 and the washer 17 against movement endwise of said crank-pin, is an apertured boss 19 provided at one end of a connection-element functioning as a needle-reciprocating link 20. The other end of the link 20 is formed with an apertured boss 21 embracing a stud-pin 22 extending laterally from and suitably secured upon a needle-bar 23. The needle-bar 23 is journaled for endwise vertical reciprocation in suitable bearings provided in the bracket-arm head 2 and disposed at opposite sides of the stud-pin 22.

The present invention relates more particularly to specially devised means for supplying lubricant to the needle-roller bearing 18. To this end, there is provided a segment-plate 25 which is detachably secured, by screws 26, upon the bracket-arm wall 4 at the crank-pin 12 side of said wall. The curved edge 25' of the segment-plate 25 is preferably slightly larger than a semicircle and the chord-edge 25'' is preferably substantially horizontal. The segment-plate 25 is circularly partly cut away at the wall 4 side thereof to provide a segmental recess 27 affording clearance for the protruding portion of the ball-bearing 6.

At opposite side, the segment-plate 25 has a cylindrical flange 28 which is concentric with the curved edge 25' and extends partly below the chord 25'' of the segment-plate. The portion 28' of the flange 28 which extends below the chord 25'' of the segment-plate is partly cut away at the ball-bearing 6 side of the flange, thereby to space the depending portion 28' of the flange from the ball-bearing 6. The flange 28 surrounds the hub-extension 10 of the crank-member 9; said flange having a central opening 29 which is slightly larger diametrically than the hub-extension 10.

The flange 28 of the segment-plate extends into an annular oil-collecting recess 30 encircling the shaft 7 and formed in the face of the crank-member 9 at the hub-extension side face thereof; the radially inner wall-face of said recess 30 being flush with and forming a continuation of the outer face of the hub-extension 10. The radially outer wall face 31 of the recess 30 is undercut to increase progressively in diameter inwardly of said recess 30.

The crank-pin 12 is partly cut away adjacent the plate-flange 28 to provide a recess 32 which forms a continuation of the recess 30 of the crank-

member 10. Opening into the crank-pin recess 32 is a lubricant-duct 33 formed in the crank-pin to extend lengthwise thereof at an inclination to the longitudinal axis of the crank-pin; the direction of inclination of the duct 33 from the recess 32 being outwardly away from the rotation-axis of the arm-shaft 7. The end of the duct 33 opposite to the recess 32 is connected by a radial crank-pin duct 34 with the needle-roller bearing face of said crank-pin.

The upper portion of the segment-plate 28 is provided with an elongate oil-well cavity 35. Extending vertically downwardly from opposite ends of the bottom wall of the oil-well cavity 35 are segment-plate apertures or ducts 36 connected to horizontal ducts 37 provided in the flange 28 of the segment-plate at diametrically opposite sides thereof and substantially at the level of the axis of rotation of the arm-shaft 7. Lubricant may be supplied to the oil-well 35 through an aperture 38, provided in the wall of the bracket-arm 1 above the oil-well.

The lubricant passes gravitationally from the oil-well 35 through the connected ducts 36 and 37, and is discharged by the ducts 37 into the crank-member recess 30. Upon rotation of the shaft 7, the oil collected in the crank-member recess 30 is centrifugally supplied to the needle-roller bearing 18 through the crank-pin inclined duct 33 and the connecting duct 34.

The spacing of the lower portion 28' of the segment-plate flange 28 from the ball-bearing 6 reduces, to a minimum conduction of oil by capillary action from the lower portion of the crank-member recess 30. The described construction definitely insures the delivery of oil from the oil-well 35 to the needle-roller bearing 18.

Having thus set forth the nature of the invention, what I claim herein is:

1. In a sewing machine, a frame including a wall provided with an opening, an antifriction bearing disposed in said opening, a rotary shaft extending through said opening and journaled in said bearing, a crank-member carried by said shaft at one side of said wall and provided in its face proximate to said wall with an oil-collecting recess, a crank-pin carried by said crank-member, a connection-element journaled upon said crank-pin, a plate secured upon said wall and having a portion thereof extending into said oil-collecting recess of the crank-member, an oil-well provided in said plate above the level of said oil-collecting recess, an oil-duct in said plate connecting said oil-well and said oil-collecting recess, and oil-conducting means connecting said oil-collecting recess and the connection-element bearing upon said crank-pin.

2. In a sewing machine, a frame including a wall provided with an opening, an antifriction bearing disposed in said opening, a rotary shaft extending through said opening and journaled in said bearing, a crank-member carried by said shaft at one side of said wall and provided in its face proximate to said wall with an annular oil-collecting recess, a crank-pin carried by said crank-member, a connection-element journaled upon said crank-pin, a plate secured upon said wall and having a flange surrounding said shaft and extending into said oil-collecting recess, an oil-well provided in said plate above the level of said oil-collecting recess, an oil-duct in said plate extending from said oil-well and through said flange to terminate in said oil-collecting recess, and a crank-member oil-duct connecting said oil-

collecting recess and the connection-element bearing upon said crank-pin, said crank-member oil-duct extending from said oil-collecting recess at an inclination away from the rotation axis of said shaft.

3. In a sewing machine, a frame having a wall provided with an opening, an antifriction bearing disposed in said opening, a rotary shaft extending through said opening and journaled in said bearing, a crank-member carried by said shaft at one side of said wall and having a cylindrical hub-portion extending toward said antifriction bearing, said crank-member being provided in its face proximate to said wall with an annular oil-collecting recess, and said oil-collecting recess having an undercut radially outer wall and having the radially inner wall thereof forming a continuation of said hub-portion of the crank-member, a crank-pin carried by said crank-member, a connection-element journaled upon said crank-pin, a plate secured upon said wall at the crank-member side thereof having a flange surrounding said hub-portion of the crank-member and extending into said oil-collecting recess, an oil supply duct extending through said flange to terminate in said oil-collecting recess, and oil-conducting means connecting said oil-collecting recess and the connection-element bearing upon said crank-pin.

4. In a sewing machine, a frame including a wall provided with an opening, an antifriction bearing disposed in said opening and protruding from one side face of said wall, a rotary shaft extending through said opening and journaled in said bearing, a crank-member carried by said shaft and having a hub-extension in engagement with the protruding portion of said ball-bearing, said crank-member being provided in the side face thereof proximate to said wall with an annular oil-collecting recess, and said oil-collecting recess having an undercut radially outer wall and having the radially inner wall thereof forming a continuation of said hub-extension of the crank-member, a crank-pin carried by said crank-member having an oil-duct connecting said oil-collecting recess with a connection-element bearing of said crank-pin, a connection-element journaled upon said crank-pin, a plate secured upon said wall at the crank-member side of said wall and having a clearance recess for the protruding portion of said ball-bearing, said plate having an annular flange surrounding said hub-extension and entering said oil-collecting recess of the crank-member, an oil-well provided in said plate above the level of said oil-collecting recess, and an oil-duct extending from said oil-well and through said flange to terminate in said oil-collecting recess of the crank-member.

5. In a sewing machine, a frame including a wall provided with an opening, an antifriction bearing disposed in said opening, a rotary shaft extending through said opening and journaled in said bearing, a crank-member carried by said shaft at one side of said wall and provided in its face proximate to said wall with an annular oil-collecting recess, a crank-pin carried by said crank-member having an oil-duct connecting said oil-collecting recess with a connection-element bearing of said crank-pin, a connection-element journaled upon said crank-pin, a plate disposed between said crank-member and said wall and having an annular flange extending into said oil-collecting recess of the crank-member, said flange surrounding said shaft and having the lower portion thereof spaced from said

antifriction bearing, and oil-conducting means in said plate terminating in said oil-collecting recess.

6. In a sewing machine having a frame including a hollow bracket-arm provided with a transverse wall, an antifriction bearing supported by said wall, a shaft extending through said wall and rotatably journaled in said antifriction bearing, a crank-member carried by said shaft adjacent said wall and provided with a crank-pin, said crank-member having the side face thereof proximate to said wall provided with an annular oil-collecting recess encircling said shaft, a needle-bar journaled for endwise reciprocation in said bracket-arm, a connection-element journaled upon said crank-pin and operatively connected to reciprocate said needle-bar, a plate secured to and disposed at the crank-member side of said wall, said plate having an annular flange encircling said shaft and extending into said oil-collecting recess, an oil-well in said plate, an oil-duct in said plate leading from said oil-well and extending through said flange to terminate in said recess, and a crank-pin oil-duct extending from said oil-collecting recess to the connection-element bearing of said crank-pin.

7. In a sewing machine having a frame including a hollow bracket-arm provided with a

transverse wall, an antifriction bearing supported by and protruding from a side face of said wall, a shaft extending through said wall and rotatably journaled in said antifriction bearing, a crank-member carried by said shaft at the side of said wall from which said bearing protrudes, said crank-member having the side face thereof proximate to said wall provided with an annular oil-collecting recess encircling said shaft, a crank-pin carried by said crank-member, a needle-bar journaled for endwise reciprocation in said bracket-arm, a connection-element journaled upon said crank-pin and operatively connected to reciprocate said needle-bar, a stationary plate disposed at the crank-member side of said wall and having a portion thereof extending into said oil-collecting recess of the crank-member, said plate being provided in its side face proximate to said wall with a recess affording clearance for the protruding portion of said antifriction bearing, an oil-well in said plate, an oil-duct formed in said plate connecting said oil-well and said oil-collecting recess, and a crank-pin oil-duct extending from said oil-collecting recess to the connection-element bearing of said crank-pin.

SYDNEY ZONIS.
